(57) **CLAIM**

We claim the ornamental design for a nitrous oxide bottle mount, as shown and described.

DESCRIPTION

FIG. 1 is top plan view a nitrous oxide bottle mount according to the present invention;

FIG. 2 is a front elevation view of the nitrous oxide bottle mount;

FIG. 3 is a bottom plan view of the nitrous oxide bottle mount;

FIG. 4 is a front elevation view like that of FIG. 2, but showing an arbitrary design rearrangement as the nitrous oxide bottle mount is shifted from a closed position to an open position;

FIG. 5 is a left side elevation view of the nitrous oxide bottle mount;

FIG. 6 is a top left rear perspective of the nitrous oxide bottle mount;

FIG. 7 is a rear elevation view of the nitrous oxide bottle mount; and,

FIG. 8 is a right side elevation; view of the nitrous oxide bottle mount.
